Patented Feb. 6, 1923.

1,444,757

UNITED STATES PATENT OFFICE.

JOSEPH H. STALEY, OF COLUMBUS, INDIANA.

ENGINE-ASSEMBLY TABLE.

Application filed March 1, 1921. Serial No. 448,878.

To all whom it may concern:

Be it known that I, JOSEPH H. STALEY, a citizen of the United States, residing at Columbus, in the county of Bartholomew and State of Indiana, have invented new and useful Improvements in Engine-Assembly Tables, of which the following is a specification.

This invention relates to tables for holding engine blocks rigidly in either vertical or horizontal position during the initial assembly of its appurtenances or repair afterwards, and the object is to provide means for quickly and securely locking the engine bed in place, and to provide foot-operated means for unlocking the table to allow the table to be rotated to bring different parts within convenient access of the workman as his work progresses.

10 A further object is to provide a more efficient and convenient holder for tools whereby work on the parts is facilitated.

A still further object is to provide a device of the above character which is simple 25 and cheap to manufacture, strong and durable, and effective in operation.

Other objects and advantages to be derived from the use of my invention will appear from the following description and claims, 30 taken with the accompanying drawing, in which—

Fig. 1 is a top plan view of my invention with the engine blocks removed. Fig. 2 is a perspective view of same with an engine 35 block in vertical position and another in horizontal position clamped thereto. Fig. 3, is a vertical section on the line 3—3 of Fig. 1. Fig. 4 is a section on the line 4—4 of Fig. 1, and Fig. 5 is a section on the line 5—5 of Fig. 1.

Like characters of reference indicate like parts in the several views of the drawing.

The base 6 and standard 7 are of integral cast iron with holes through the base for bolting same firmly to the shop floor. The top of the standard terminates with a horizontal plate 9' upon which the table 8 is pivotally mounted, and surrounding the pivot in both table and plate is a circular ball race in which ball bearings 9 are mounted, the lower half of the race being in the plate 9' and the upper half being in a circular concentric portion 10. The portion 10 has radial teeth which are engaged by a dog

11, vertically mounted in a bracket extension 55 from the standard, and pressed normally upward by a spring 13. A stem 14 of the dog is pivotally secured to a foot lever 15 which is pivoted to ears at the junction of the standard with the base. When the dog 60 is withdrawn by a pressure of the workman's foot the table is free to be rotated by hand and will be easily moved by reason of the ball bearings on which it is mounted.

Integral with the face of the table 8 adjacent a straight edge thereof are the upstanding lugs 16, 16, and inwardly of the table therefrom a distance sufficient to receive between them the widest engine block are the like pair of lugs 17, 17. When narrower 70 engine blocks are placed the unoccupied space between it and the lugs is built out with furniture and wedges in the usual manner. Passing through the table adjacent the lugs 16, 17, are screws 18, for levelling the 75 block before it is clamped tight. Opposite each end of the rectangle marked by the lugs 16, 17, are the blocks 19 which are integral with the table and have a dowel pin p 80 at their upper ends to enter a corresponding socket in the end of a clamp bar 20, having a middle opening in which the eye of an eyebolt 21 is pivoted. The bolt extends through a hole in the table and through a threaded hole in a hand wheel 22 which bears against 85 the under side of the table. The inner end of the bar 20 is adapted to bear upon an offset portion of the engine block, such as the offset for the water jacket, and clamp the block to the table by tightening the hand 90 wheel on the eyebolt.

The above described means is that provided for securing an inverted engine block to the table 8, and on the other side of the table I provide the following means for securing a block in a horizontal position. This comprises a pair of blocks 23, 23, preferably secured to the table in an adjustable manner by bolts 24 passing through slots 25. Inwardly of the table are the ribs 26, 26, one or the other of which will take the engine flange, in the manner shown in Fig. 4, to concentrate the bearing area under a clamp bar 27. The latter has a middle hole for a bolt 28 which passes through a hole in the table 105 8 and has its threaded end received by a screw wheel 29. The opposite end of the bar 27 rests upon a cam on a rock shaft 30

mounted between suitable ears on the table. The shaft is rocked by a hand lever extension 31.

Slots 32 and 33 are formed through the table 8 to receive the workman's tools which are hung therein by passing their handles or other convenient and suitable portions therethrough.

The manner of using my invention is so apparent from what has been said when read in connection with the drawing, that further description and explanation is deemed unnecessary.

Having thus fully described my invention, what I claim as new and wish to secure by Letters Patent of the United States, is—

1. In an engine-assembly machine, a table, a double row of projections thereon receiving the engine block between them, means operated from below the table to level the block, and clamp-means at three points to retain the block in a given position.

2. In an engine-assembly machine, a table, adjustable means thereon to prevent displacement of the outer portion of an engine-block placed on its side on the table, a clamp-plate to force the inner portion of the block toward the table, and a rocking-cam operating against the plate to tighten it against the block.

3. In an engine-assembly machine, a table, adjustable block-means thereon to prevent lateral displacement of the outer portion of an engine-block placed on its side on the table, and cam operated clamp-means in-

wardly of the table to engage the block midway of its ends and lock the block to the table.

4. In an engine-assembly machine, a table, adjustable block-means thereon to prevent lateral displacement of the outer portion of an engine-block placed between them, and a clamp means to lock the block to the table comprising a plate, adjustable means for connecting the plate with the table, and a lever-operated rock-shaft with a cam to raise one end of the plate and lower the other end into contact with the block.

5. In an engine-assembly machine, a table, a plurality of lugs in a double row between which the engine-block is placed, set screws through the table to level the block and a pair of screw-tightened clamps engaging the ends of the block and a cam-tightened clamp engaging the middle and other side of the block from said screw-clamps.

6. In an engine assembly machine, a horizontal table having engine adjusting and securing means on its upper side and a vertical pivot on its lower side, a vertical standard on which the table is pivotally mounted, a circle of teeth in a horizontal row on the table concentric with the pivot, a spring-pressed dog engaging with the teeth, and means operated by the foot of the workman for disengaging the dog.

Signed at Columbus, Indiana, this the 21st day of February 1921.

JOSEPH H. STALEY.
